(73) Assignee: **Dansk Mik Papir A/S**, Holstebro (DK)

Primary Examiner — Patricia Palasik
(74) *Attorney, Agent, or Firm* — William J. Sapone; Ware Fressola; Maguire & Barber LLP

(**) Term: **14 Years**

(57) **CLAIM**

I claim the ornamental design for a machine for cutting paper and rollers therefore, as shown and described.

(21) Appl. No.: **29/389,982**

DESCRIPTION

(22) Filed: **Apr. 19, 2011**

FIG. 1 is a front perspective view of the machine for cutting paper showing my new design,

(30) **Foreign Application Priority Data**

FIG. 2 is a front view thereof;

Oct. 26, 2010 (EM) 001242531

FIG. 3 is a right side view thereof;

(51) **LOC (9) Cl.** **15-09**

FIG. 4 is a top view of a roller conveyor included in the machine for cutting paper, with a portion of the machine shown in broken lines for clarity of the disclosure, the bottom view being a mirror image thereof;

(52) **U.S. Cl.**

FIG. 5 is a top view of a powered drive roller therefore, shown removed from the machine for clarity of the disclosure;

USPC **D15/127**

FIG. 6 is a right side view of the powered drive roller of FIG.

(58) **Field of Classification Search**

5;

USPC D15/127; D18/34.1, 34.3, 34.7, 34.8,
D18/34.9; 30/151, 162, 286, 290, 294, 319;
83/29, 167, 276, 277, 278, 281, 291,
83/321, 322, 334, 417, 423, 449, 544, 565,
83/614, 620, 635, 674, 687, 691, 745, 859,
83/927

FIG. 7 is a left side view of the powered drive roller of FIG. 5;

See application file for complete search history.

FIG. 8 is a top view of an idle roller for the roller conveyor of
